UNITED STATES PATENT OFFICE.

CORNELIUS SZILVAY, OF BUDAPEST, HUNGARY.

APPARATUS FOR EXTINGUISHING FIRE.

Application filed December 24, 1924, Serial No. 757,834, and in Hungary December 29, 1923.

This invention relates to an apparatus for extinguishing fire.

It is well known that with certain kind of fire-disaster it is much more preferable to use a powdery substance for extinguishing the fire than to use water for the same purpose. With this method of extinguishing fire the extinguishing powder generally has been blown on to the burning objects by means of indifferent gases for example such as carbonic acid stored under pressure in bottles or the like. This method of extinguishing fire though very efficacious and doing no harm to the objects saved by the fire is associated with the disadvantage that the carbonic acid after a certain period of being kept stored escapes from the storage bottles, and this circumstance apart from the loss of material may become very dangerous by the fluid under pressure being no longer present when necessary. A further disadvantage of this known method of extinguishing fire is that only a small quantity of fluid under pressure may thus be ready for use so that in case of big fires the carbonic acid becomes quickly consumed whereby a stoppage in extinguishing is caused.

The object of the present invention is to provide an apparatus in which the exhaust gases of a combustion engine are employed for blowing a fire extinguishing powder to the place of fire.

This invention consists in the construction and arrangement of the parts of the apparatus as hereinafter described and pointed out in the claims.

In the accompanying drawing one form of a fire engine adapted to carry the method according to the invention into effect is diagrammatically shown by way of example.

Referring now to the drawing 1 indicates the powder receptacle the extinguishing powder being conveyed from this receptacle by means of a conveyor 2 to the nozzle 3. 4 indicates a combustion engine the exhaust gases of which are escaping through the pipe 5. At 6 the pipe 5 opens into a tube-cooler 7. While passing this cooler the exhaust gases of the combustion engine are cooled and thus they are enabled to leave the cooler 7 suitably cooled through pipe 8. The pipe 8 opens into a compressor 9 driven by shaft 10 of the engine 4, the same shaft also driving the conveyor 2 by means of the belt-gearing 11. The compressor 9 compresses the gases sucked in through the pipe

8 to a suitable pressure and conveys them through the casing 12 to the nozzle 3 the extinguishing powder conveyed to said nozzle being blown by said compressed gases into the socket 13 to which is attached in a well known manner the hose used when extinguishing fire. The cooler 7 for cooling the exhaust gases may be of any desired construction; in the drawing an air-cooler having a suitable tubing is shown by way of example the air entering through the inlet 16 being sucked through the tubing 14 by means of an exhauster 15. The exhaust gases sucked through the cooler 7 by the compressor 9 are passed between the tubing 14 so that they are cooled by the air passing the pipes 14. The exhauster 15 is driven by shaft 10 of the engine 4 by means of the belt-gearing 17. It is understood that the cooler may also be constructed like a water-cooler in the same manner as are the radiators or in any other way. In the pipe 18 through which the cooler 7 communicates with the exhauster 15 there is arranged a valve 19 establishing communication between the cooler and the exhauster in its shown position. By turning the valve 19 from its position shown in the drawing by 90° communication is established between the exhauster and the atmosphere and the suction-pipe of the exhauster is sucking in air through the socket 20. After the fire has been extinguished the exhauster 15 can be used to suck out the gases already blown into the place of the fire to extinguish same, by fastening to the socket 20 a suction-hose leading to said place of fire. Thus, after the fire has been extinguished the rooms can be made accessible in a few minutes.

In certain cases where the exhaust gases of the combustion engine are not sufficient to convey the extinguishing powder or if in consequence of the operation of the compressor 9 the pressure in the pipe 5 is lowered beyond the necessary degree, the relief-valve 21 located at the outside opening of the pipe 5 opens whereby some part of the air sucked in through the radiator of the engine 4 is led into the pipe 5 and being mixed up with the exhaust gases enters the compressor 9 to be further conveyed to the nozzle 3. This quantity of air is insufficient for rousing the fire since when reaching the place of the fire it is strongly diluted by being mixed up with the exhaust gases consisting chiefly of carbonic acid and nitrogen.

The relief-valve 21 is charged with a spring in a well known manner so that it closes when the pressure in the pipe 5 is raised to a certain degree whereupon only the exhaust gases can reach the place of fire.

The whole apparatus described above is mounted on a wagon driven by the engine 4 so that it can be used as a fire-engine.

Claims:—

- 10 1. A fire extinguishing apparatus comprising a combustion engine, a pipe leading away from the exhaust gases of said combustion engine, an air cooler connected to said pipe and having a tubing, an exhauster actuated by said combustion engine sucking air through said tubing, a nozzle, a compressor connected to said cooler, sucking the exhaust gases from the said cooler and conveying them to the nozzle, a receptacle for extinguishing powder, means for conveying the extinguishing powder from said receptacle to the said nozzle, means in connection with the said nozzle and with the compressor for 15 mixing the extinguishing powder with the exhaust gases and means for conducting the mixture to the fire.
- 20 2. A fire extinguishing apparatus comprising a combustion engine, a pipe leading away from the exhaust gases of said engine, a cooler

for said exhaust gases, means for circulating a cooling medium through said cooler and operated by said engine, a nozzle, a compressor conveying the exhaust gases having passed from the cooler to the nozzle, and 25 driven by said engine, a receptacle for extinguishing powder, means for conveying said powder from said receptacle to said nozzle, means in communication with said nozzle and with the compressor for mixing the extinguishing powder with the exhaust gases, and means for conducting the mixture to the fire.

3. A fire extinguishing apparatus comprising a combustion engine, a pipe leading away the exhaust gases of said engine, a cooler for said exhaust gases, means for circulating a cooling medium through said cooler and operated by the engine, a compressor driven by said engine, a pipe connecting said cooler with said compressor, a receptacle for fire extinguishing powder provided with a discharge nozzle, said nozzle communicating with said compressor, and a feeding device in said receptacle for feeding the powder 50 into said nozzle, and operated by said engine.

In testimony whereof I have signed my name to this specification.

CORNELIUS SZILVAY.
